DESIGN FOR A VELOCIPED

Herman L. Kraeft, Cleveland Heights, Ohio, assignor to The Murray-Ohio Manufacturing Company, Cleveland, Ohio, a corporation of Ohio

Application May 2, 1939, Serial No. 84,716

Term of patent 7 years

To all whom it may concern:

Be it known that I, Herman L. Kraeft, a citizen of the United States, residing at Cleveland Heights, county of Cuyahoga, and State of Ohio, have invented a new, original, and ornamental Design for a Velocipede, of which the following is a specification, reference being had to the accompanying drawing, forming a part thereof.

The single figure of the drawing is a perspective view of a velocipede, showing my new design.

I claim:

The ornamental design for a velocipede, as shown.

HERMAN L. KRAEFT.
